J. H. BUCHANAN.

Stove.

No. 21,938.

Patented Nov. 2, 1858.

UNITED STATES PATENT OFFICE.

J. H. BUCHANAN, OF NEW CONCORD, OHIO.

STOVE.

Specification of Letters Patent No. 21,938, dated November 2, 1858.

To all whom it may concern:

Be it known that I, J. H. BUCHANAN, of New Concord, in the county of Muskingum and State of Ohio, have invented a new and useful Improvement in Ventilating-Stoves; and I do hereby declare that the following is a full, clear, and exact description of the same, reference being had to the accompanying drawings, forming a part of this specification, in which—

Figure 1, is a perspective view of my improved stove, and Fig. 2, is a vertical section of the same.

Similar letters of reference, in each of the several figures, indicate corresponding parts.

The object of my invention is to provide a stove which combines the advantages of the grate with the economy of an air tight stove, and which will afford from the same amount of fuel more light and heat than either, and especially be more conducive to health, require less material in its construction and suit any degree of draft.

My invention embraces the arrangement consisting of the concave bed or ash pit of larger diameter than the grate and constructed with supporting lugs or ledges; semi-spherical open top-legged-grate or fire chamber with draft space existing between it and the ash pit or bed, and flaring stove pipe appearing as a continuation of the grate and furnished with a transverse feed and draft door and arranged above the fire grate or chamber and made adjustable in a vertical line with the fire grate on a vertical standard, all for the purposes hereinafter stated.

To enable others, skilled in the art, to make and use my invention, I will proceed to describe its construction and operation.

A, represents the base of the ash pit; B, the ash pit made of cylindrical form and furnished with supports *a, a, a*, on its interior surface.

C, is the fire chamber made partly spherical and of open grate work, and furnished with legs *b, b, b*, which rest upon the supports *a, a, a*, as shown. This grate is of smaller diameter than B, so that a draft space *m*, shall exist when it is in proper position, and the legs are made narrow so

that the draft shall have a chance to circulate under the grate or fire chamber. The bottom of the fire chamber is perforated so as to admit a draft up through it as illustrated by the arrows. By thus arranging the fire chamber, its open sides are exposed and it can be readily lifted out of the ash pit.

D, is a section of stove pipe. This section of pipe is fitted loosely at its upper end over the other portion of the pipe so as to be capable of being moved freely up and down. Its lower end is made flaring or partly spherical so as to have in its outline, a similar form as that of the fire chamber, and thus when applied appear as a continuation of the fire chamber.

E, is a vertical standard projecting up from the base of the ash pit. To this standard, the movable section of pipe is attached by means of an eye *c*, and set screw *d*, as shown. By thus arranging the movable section of pipe, it can be raised or lowered on the standard and thus made to create greater or less draft and to perfectly ventilate the room. By raising the section of pipe, the upper part of the fire is exposed and thus light and comfort afforded. The draft is decreased, but the ventilation increased. By lowering the section of pipe the top of the fire is hidden and the ventilation impaired, but the draft increased. The complete lowering of the pipe only takes place when the fire is being started and on retiring to bed.

F, is a door in the section of pipe for the introduction of fuel. This intermediate door, also, by being left open when the pipe is completely down in order to insure safety, will destroy the draft to the fire chamber and thus prevent the fuel being rapidly consumed during the night.

What I claim as my invention and desire to secure by Letters Patent, is—

The arrangement consisting of the concave bed or ash pit A, of larger diameter than the grate and constructed with supporting lugs or ledges *a, a*; semi-spherical open top grate or fire chamber C, *b, b*, with draft space *m*, existing between it and the ash pit or bed A; and flaring stove pipe D, appear-

ing as a continuation of the grate and furnished with a transverse feed and draft door F, and arranged above the fire grate and made adjustable in a vertical line with the fire grate on a vertical standard; all for the purposes herein stated and substantially as set forth.

The above specification of my improvement in ventilating stoves signed by me this 28th day of July 1858.

J. H. BUCHANAN.
